DESIGN FOR A FACETED GAME CONTROL ELEMENT

Rudolph Peukert, Toronto, Ontario, Canada

Application December 22, 1947, Serial No. 143,279

Term of patent 7 years

(Cl. D34—5)

To all whom it may concern:

Be it known that I, Rudolph Peukert, a Subject of the King of Great Britain, residing in the city of Toronto, in the county of York, in the Province of Ontario, Canada, have invented a new, original, and ornamental Design for Faceted Game Control Element, of which the following is a specification, reference being had to the accompanying drawings, forming a part thereof.

In the drawings:

Figure 1 is a top plan view of the game control element.

Figure 2 is a bottom plan view thereof, and Figure 3 is a side elevation thereof.

I claim:

The ornamental design for a faceted game control element, substantially as shown.

RUDOLPH PEUKERT.
